ABSTRACT: A delay-line memory using a magnetostrictive delay-line, in which a pair of bidirectional pulses derived from the delay-line by the use of a magnetostrictive-electric transducer and having successive reverse polarities with respect to the successive polarities of a preceding bidirectional pulse are converted into a square wave output signal by a bistable circuit performing hysteresis switching action triggered at times when the instantaneous level of the bidirectional pulses exceeds a first reference level determined between the zero level and the plus peak level of the bidirectional pulses and descends a second reference level determined between the zero level and the minus peak level of the bidirectional pulses.

MAGNETOSTRICTIVE DELAY-LINE MEMORY

This invention relates to a magnetostrictive delay-line memory comprising a magnetostrictive delay-line and means for regenerating and reinserting digital information into the delay-line.

In a case where a rectangular pulse is applied to a magnetostrictive delay-line, bidirectional pulses derived from a transducer coupled with the delay-line are delayed, by a delay time t , respectively from the rise instant and the termination instant of the inserted rectangular pulse. In one conventional delay-line memory of this type (e.g.; Japan Pat. Publication No. 8254/1964), the bidirectional pulses are applied to two level detectors respectively having a plus reference level and a minus reference level, so that plus pulses are obtained from one of the two detectors with respect to the plus reference level in synchronism with the instants when the instantaneous levels of the bidirectional pulses reach the plus reference level, and so that minus pulses are obtained from the other of the two detectors with respect to the minus reference level in synchronism with the instants when the instantaneous levels of the bidirectional pulses reach the minus reference level. Accordingly, the rectangular pulse inserted in the delay-line can be regenerated, delayed by a delay time t , by setting the state of a bistable circuit to the state "1" in synchronism with the former one of the plus pulses and by resetting the state of the bistable circuit to the state "0" in synchronism with the later one of the two minus pulses. However, this conventional circuitry of the conventional regeneration technique for delayed pulses is complicated.

An object of this invention is to provide a delay-line memory reliably regenerating delayed pulses by regeneration means of simple construction.

In accordance with the characteristic feature of this invention, the regeneration means of the delay-line is provided with a bistable trigger circuit, such as Schmitt trigger, that converts a pair of bidirectional pulses which are successively derived from the delay-line and have successive reverse polarities with respect to the successive polarities of a preceding bidirectional pulse into a square-wave output signal by a hysteresis switch action triggered at a time when the instantaneous level of the input voltage of this bistable trigger circuit exceeds a predetermined first reference level or descends below a predetermined second reference level. In other words, delayed pulses can be readily regenerated with simple construction by utilizing the hysteresis switching action of the bistable trigger circuit.

The principle of this invention will be better understood from the following more detailed discussion taken in conjunction with the accompanying drawings, in which:

FIG. 1 is a block diagram for illustrating an embodiment of this invention;

FIG. 2 shows time charts explanatory of the operation of the embodiment of this invention;

FIG. 3 is a circuit diagram for illustrating an example of the bistable trigger circuit used in the delay-line memory of this invention;

FIG. 4 is a circuit diagram for illustrating another example of the bistable trigger circuit used in the delay-line memory of this invention;

FIGS. 5A and 5B show time charts and a characteristic diagram explanatory of the operation of the example shown in FIG. 3; and

FIG. 6 shows a characteristic diagram explanatory of the operation of the example shown in FIG. 4.

With reference to FIG. 1, an example of this invention comprises a magnetostrictive delay-line 1, damping means 2 and 3 arranged respectively the ends of the delay-line 1 to damp reflected waves from the delay-line 1, a pulse generator 4 generating pulses to apply the delay-line 1, an electromagnetostriction transducer 5 (e.g.; a coil arranged concentrically with the delay-line 1) to apply an ultrasonic shock wave in response to the pulse generated from the pulse generator 4 to the delay-line 1, a magnetostriction-electric transducer 6 to

pick up, as an electric signal, the shock wave travelling through the delay-line 1 in the direction of an arrow A_6 , and amplifier 7 amplifying the electric signal picked up, a detector 8 for detecting desired pulses from the amplified electric signal, an input-output means 10 to take out readout pulses and to receive input pulses, and a read-write means 9 for reading out the detected pulses to apply the input-output means 10 and for controlling the pulse generator 4 to write-in the input pulses or the readout pulses again in the delay-line 1.

A square wave v_1 shown in FIG. 2 is an example of the square wave generated from the pulse generator 4 and having a rise portion 11, a flat portion 12 lasting a duration T and a termination portion 13. It can be considered that this square wave is delayed as shown by a dotted line through the delay-line 1 if it is assumed that this square wave travels through the delay-line 1 as it is. Accordingly, a pair of bidirectional pulses v_2 are obtained at the output of the amplifier 7. In this case, peak portions 14 and 15 are obtained in response to the rise portion of the square wave delayed, and peak portions 16 and 17 are obtained in response to the termination portion of the square wave delayed. It will be seen that the bidirectional pulse comprising peak portions 16, 17 has successive reverse polarities (i.e. plus and minus) with respect to the successive polarities (i.e. minus and plus) of the preceding bidirectional pulse comprising peak portions 14, 15. These bidirectional pulses (v_2) are applied to the detector 8. This detector 8 is a bistable trigger circuit, such as Schmitt trigger, that has a first reference level 18 between the zero level and the plus peak level (15, 16) and a second reference level 19 between the zero level and the minus peak level 14, 17 so that a pair of the bidirectional pulses v_2 are converted into a square wave v_3 by hysteresis switching action triggered at a time 20 when the instantaneous level of the bidirectional pulses v_2 exceeds the first reference level 18 and a time 21 when the instantaneous level of the bidirectional pulses v_2 descends the second reference level 19. This regenerated square wave v_3 has a rise portion 22, a flat portion 23 lasting a duration T and a termination portion 24 which correspond respectively to the rise portion 11, the flat portion 12 and the termination portion 13 of the square wave v_1 . Accordingly, the regenerated square wave v_3 has the same duration T as that of the square wave v_1 and delayed by a delay-time t from the square wave v_1 . This regeneration of the delayed pulse v_3 can be performed without disturbance of noise since the bistable trigger circuit has a hysteresis switching action.

FIG. 3 shows an example of a Schmitt trigger using transistors Tr_1 and Tr_2 employed as the bistable trigger (detector 8). This Schmitt trigger has, as shown in FIG. 5A, usually a first reference level UTL and a second reference level LTL and converts an AC input signal v_4 applied to an input terminal I thereof into a square wave output signal v_5 by hysteresis switching action triggered at a time when the instantaneous level of the AC input signal v_4 exceeds the first reference level UTL or at a time when the instantaneous level of the AC input signal descends the second reference level LTL . In other words, the output voltage v_5 obtained at the output terminal O of the Schmitt trigger varies as shown by arrows A_1 , A_2 , A_3 and A_4 or arrows A_5 , A_6 , A_7 and A_8 respectively in FIG. 5B if the input voltage v_4 applied to the input terminal I increases or decreases. Accordingly, this Schmitt trigger has a hysteresis characteristic indicated by a difference voltage V_h between the two reference levels UTL and LTL .

FIG. 4 shows another example of a bistable trigger circuit formed by use of a high-gain single-ended amplifier which has two differential inputs. One example of this single-ended amplifier is an operational amplifier 30, which has two differential input terminals t_3 and t_4 , and an output terminal t_5 . An input signal e_1 and a reference level $-E$ is applied to one (t_3) of the input terminals through respectively resistors R_{11} and R_{12} , and an output voltage e_3 thereof is fed back through bleeder resistors R_{13} and R_{14} to the other (t_4) of the input terminals as the positive feedback signal so that the gain of the operational amplifier 30 is raised without oscillation. In this circuit, if the

respective resistances r_{11} and r_{12} of the resistors R_{11} and B_{12} are equal to each other, a voltage e_2 appearing at the input terminal t_3 can be indicated as follows:

$$e_2 = \frac{r_{12}}{r_{11} + r_{12}} (e_1 - E) = \frac{1}{2}(E_1 - E)$$

The output voltage e_3 is limited in the negative region or in the positive region at a time when the level of the voltage e_2 reaches a first reference level UTL or a second reference level LTL as shown in FIG. 6. Accordingly, this circuit acting as an operational trigger can be employed as the detector 8 in this invention.

As mentioned above, a delayed pulse can be readily regenerated, by no use of a complicated circuitry, in accordance with the feature of this invention in which a bistable trigger circuit having a first reference level and a second reference level is employed to perform hysteresis triggering determined by the two reference levels. In this bistable trigger circuit, the two reference levels are determined so as to slice the bidirectional pulses v_2 at respective intermediate levels between the zero potential and the plus peak level of the bidirectional pulses v_2 and between the zero potential and the minus peak level of the bidirectional pulses v_2 as shown in FIG. 2.

What we claim is:

1. A delay-line memory comprising:
a magnetostrictive delay-line,

insertion means coupled to the magnetostrictive delay-line for inserting a pair of shock waves into the magnetostrictive delay-line in response to each square pulse to be delayed,

magnetostrictive-electric transducer means coupled with the magnetostrictive delay-line for producing a pair of bidirectional electric pulses, the latter of which has successive reverse polarities with respect to the successive polarities of the former bidirectional pulses, in response to said pair of shock waves travelling through the magnetostrictive delay-line, and

a bistable trigger circuit which is connected in the output of said transducer means and which converts said pair of bidirectional pulses obtained at the output of the transducer means into a square wave output signal by hysteresis switching action triggered at times when the instantaneous level of the bidirectional pulses exceeds a first reference level determined between the zero level and the plus peak level of the bidirectional pulses and descends below a second reference level determined between the zero level and the minus peak level of the bidirectional pulses.

2. A delay-line memory according to claim 1, in which the bistable trigger circuit is a Schmitt amplifier.

25 3. A delay-line memory according to claim 1, in which the bistable circuit is an operational trigger.
